DESIGN FOR A DRAFT ARM FOR BEVERAGE DISPENSERS

Jack J. Booth, Dallas, Tex.

Application November 8, 1943, Serial No. 111,619

Term of patent 7 years

To all whom it may concern:

Be it known that I, Jack J. Booth, a citizen of the United States, residing at Dallas, in the county of Dallas, State of Texas, have invented a new, original, and ornamental Design for a Draft Arm for Beverage Dispensers, of which the following is a specification, reference being had to the accompanying drawing, forming part thereof.

Figure 1 is a side elevational view of a draft arm for beverage dispensers, showing my new design;

Figure 2 is a front elevational view; and
Figure 3 is a top plan view thereof.

I claim:

The ornamental design for a draft arm for beverage dispensers, as shown.

JACK J. BOOTH.
